UNITED STATES PATENT OFFICE.

THEODORE P. McCARTHY, OF NEW YORK, N. Y.

BAG HOLDER AND DISPLAY RACK.

Application filed March 25, 1927. Serial No. 178,269.

This invention relates to receptacles and has particular reference to a combined holder for paper bags and display rack for merchandise.

5 One of the principal features of the present invention is to provide a bag holder composed of a plurality of units of different size having a means of connection which permits of selective combinations of the various unit sizes in accordance with the needs of the particular user.

More specifically the invention comprehends a bag holder including units of different sizes adapted to be arranged in superimposed relation and in which said units include top, bottom, side and rear walls, the forward end of each unit being open for the insertion of the bags and removal of the same from the units, interengaging means 20 being provided respectively on the top and bottom walls of the associated units, which means is so constructed as to allow for association and disassociation by relative sliding movement in a horizontal plane.

25 The invention further includes shelves associated with the side and end walls of the units to define a supporting rack for articles of merchandise whereby the device may be employed in a double capacity.

30 Other objects reside in the simplicity of construction of the device, the economy with which the same may be produced, and the general efficiency derived therefrom.

With the above recited and other objects in view reference is had to the following specification and accompanying drawings in which there is exhibited one example or embodiment of the invention which is in no way intended as a limitation upon the scope 40 of the appended claims as it is to be clearly understood that variations and modifications which properly fall within the scope of said claims may be resorted to when found expedient.

45 In the drawings:—

Figure 1 is a perspective view of a bag holder illustrating a plurality of associated units of various sizes and showing the same equipped with merchandise display shelves;

50 Fig. 2 is a transverse sectional view therethrough with the shelves removed;

Fig. 3 is a view similar to Fig. 2, illustrating an arrangement in which a small and a large unit may be associated;

55 Fig. 4 is a side view of the holder as illustrated in Fig. 1.

Referring to the drawings by characters of reference, 10, 11, 12 and 13 designate generally units of varying sizes adapted to respectively receive paper bags or other articles of varying sizes, and each of which units includes side walls *a*, top and bottom walls *b* and *c*, and a rear end wall *d*. The units vary in size both as to their cross-sectional area and their length, and the same are adapted to be arranged in superposed relation with the largest sized unit at the bottom and the smallest sized unit at the top, and with the intermediate units graded according to their size. In order to provide 70 means for associating the units against accidental displacement, which means permits of the assembling of the units with each other irrespective of their relative sizes, the bottom wall *c* of each unit is formed with 75 one or more longitudinally extending tongues 14, while the top wall *b* of each unit is formed with one or more grooves 15, the shapes of the tongues and grooves being such that they may be engaged by a longitudinal 80 sliding movement of the units in a parallel plane. More specifically, the tongues and grooves are of dovetailed or equivalent shape. The tongues extend from the rear wall *d* forwardly and terminate at a point 85 in rear of the front open end of the units, while the grooves similarly extend through the rear end and terminate at a point spaced from the front open end of the units. In practice, it is preferable to employ a pair or 90 more tongues and grooves for each unit, in which instance the tongues and grooves of every unit will be spaced apart a similar distance so that the interchanging of interassociation of the units may be accomplished irrespective of their size. It is also to be understood that the rear walls *d* of the several units when assembled, will be disposed in the same plane, while the open forward ends of the units will be stepped back according 95ingly.

In order to increase the usefulness of the device, shelves 16 are detachably and adjustably associated with the units, said shelves being provided with an inner marginal flange 17 attached by bolts 18 to the side and end walls *a* and *d*.

In some instances where the holder is to be supported from a vertical wall, a supporting plate 19 is provided which is attached to the rear wall *d* and which protrudes above the top wall of the uppermost

unit, the said plate having apertures 20 through which nails or other fastening devices may extend. The shelves are designed to support articles of merchandise for display purposes, and when combined with the holder, make up a display rack for said articles.

What is claimed is:

1. A combined bag holder and display rack, including a plurality of superimposed box-like units having upper walls, lower walls extending beyond the upper walls, side walls and a rear end wall, and having an open forward end, the units being of varying cross sectional area and length, shelf members projecting laterally from the side and end walls of each of the units, having detachable and adjustable means of connection with said side and end walls.
2. A combined bag holder and display rack, comprising a plurality of box-like

units of varying cross sectional area and length and open at the forward end, said units being arranged one upon the other in step form, shelf members at the sides and rear ends of the units, said shelf members having inner marginal flanges, and means for securing the flanges of the shelf members to the said units.

3. A bag holder, comprising a plurality of superimposed units each having a top, bottom and rear end wall and side walls, the front end of the bottom wall projecting beyond the top wall, the units having open forward ends and being of different lengths and widths, and interengaging means on the top and bottom of the units for slidably and detachably securing them together, said means being so disposed on the units that any one of the units can be mounted on any other unit.
